UNITED STATES PATENT OFFICE

CHRISTIAN FREDRIK GRÖNER, OF OSLO, NORWAY

DAM

Application filed June 11, 1929, Serial No. 370,072, and in Norway May 11, 1929.

The present invention relates to an improvement in dams, and the object of the invention is to provide improved means for repairing leaking dams.

5 In cases where old dams of stone, concrete or the like have developed leaks, it is customary to repair the same either by the injection under pressure of a suitable concrete mixture in the body of the dam; or by providing the upstream face of the dam with a fresh water tight layer of concrete.

None of these methods are quite satisfactory, the injection system being very expensive and not thoroughly reliable, and the other 15 system having the drawback that the contractions and expansions of the layer on the upstream face of the dam differ from those of the dam itself, so that fissures and ruptures of the new layer will develop.

20 In accordance with the present invention the reconditioning of a leaking dam takes place by placing on the upstream side of the dam a thin water tight wall which is supported by the dam itself in such a manner that it is 25 free to expand and contract in its own plane independent of the dam.

It is preferred to erect the new tight wall at a certain distance from the upstream face of the old dam, the pressure on the water tight 30 wall being transmitted to the dam proper by means of columns distributed over the pressure area and being adapted, owing to their own elasticity or to their connection with the dam and tightening wall, to yield in planes 35 vertical to their axis.

The tightening wall may, however, also be erected in close proximity to the upstream dam face, so long as the pressure transmitted from the tightening wall to the upstream dam 40 face is taken up by means which permit the contraction and expansion of the tightening wall in its own plane independent of the dam.

An embodiment of the invention is illustrated on the drawing, showing diagrammatically a cross section through a dam repaired in accordance with the present invention.

1 indicates the dam to be repaired and 2 is a tightening wall which may be constructed of reinforced concrete, sheet iron or other material, and which is preferably tightly embed-

ded as indicated by 3 in the rock in front of the upstream dam face 4.

The water pressure on the tightening wall 2 is taken up by means of columns 5 of a suitable material, said columns being sufficiently thin to offer no resistance to contractions or expansions of the dam in a plane vertical to the axis of the columns.

Claim.

A permanent dam comprising the combination 60 with a main concrete dam adapted to withstand all the load of the water pressure, of a thin water tight wall located a certain distance away from the upstream face of the dam, and means for supporting the thin wall 65 against the dam including a number of independent columns adapted to yield in all directions in such a manner that the said thin wall is permitted to expand or contract in its own plane independent of the main dam.

In testimony whereof I affix my signature.
